UNITED STATES PATENT OFFICE.

GEORGE BECHERER, OF ST. LOUIS, MISSOURI.

DESIGN FOR A HEEL-PLATE.

55,971.

Specification for Design.

Patented Aug. 10, 1920.

Application filed December 19, 1917. Serial No. 207,977. Term of patent 3½ years.

To all whom it may concern:

Be it known that I, GEORGE BECHERER, a citizen of the United States of America, residing at St. Louis, in the State of Missouri, have invented a new, original, and ornamental Design for Heel-Plates, of which the following is a specification, reference being had to the accompanying drawing, forming a part thereof.

The drawing is a perspective view of a heel plate, showing my new design.

I claim:

The ornamental design for a heel plate substantially as shown.

In testimony that I claim the foregoing I hereunto affix my signature.

GEORGE BECHERER.
